UNITED STATES PATENT OFFICE

JOHN F. BENTLEY, OF DETROIT, MICHIGAN

COMBINATION FAUCET

Application filed August 15, 1928. Serial No. 299,748.

This invention is a combination water faucet, the main object being to provide a faucet of this kind in a relatively simple, practical and durable form of construction, and where-
6 in means are embodied for drawing through a common nozzle, either hot, cold or warm water.

In the drawing

- 10 Figure 1 is a plan view;
Figure 2 is a vertical section on the line 2—2 of Figure 1;
Figure 3 is a vertical section on the line 3—3 of Figure 1;
15 Figure 4 is a horizontal section on the line 4—4 of Figure 3.

The invention comprises a cylindrical housing 1 having the oppositely positioned elongated hot and cold water ports 2 and 3 which are conventionally connected with the hot 20 and cold water supply pipes 4 and 5. A nozzle sleeve 6 is formed integrally in the bottom of the housing 1, and the upper and inner end of this sleeve immediately inside the housing is formed into a beveled annular 25 valve seat 7. A tubular water nozzle 8 is rotatably and slidably seated through the sleeve 6 with a water tight joint. A circular cover 9 is fastened with set screws 10 upon the top of the housing 1, the same having an 30 integral, upwardly extended valve cage 11 from the base of which project two oppositely positioned studs 12.

A handle cap 13 is rotatably seated over the cage 11, the same having an annular 35 groove 14 formed around the inner periphery thereof near the open end, and which is adapted to slidably receive the studs 12 for retaining the cap rotatably in place upon the cage 11. Oppositely positioned entrance slots 15 40 provide means for inserting the studs 12 into the groove 14. The cap 13 is formed with an ear 16 which engages the recess 17 formed in the handle 18, the handle being lockingly secured to the ear by a pin 19 passed through 45 the handle and the said ear. The ear 16 is provided with a notch 20 at its forward edge into which plays the nose 21 of a latch 22 which is slidably mounted within the forward end of the recess 17. A coil spring 23 within 50 the recess 17 underneath the latch 22 and

bracer between the margin 24 of the recess and the depending lip 25 of the said latch, normally retracts the latch 22 from the notch 20. A thumb piece 26 is mounted upon the shank 27 of the latch 22, which shank projects upwardly through a slot 28 leading into said recess 17, and means are thus afforded for pushing the nose 21 of the latch into the notch 20. This is done when the handle 18 is depressed, and serves to hold the handle 60 in such depressed position when desired for purposes later to be explained.

The rear end of the handle is flattened into the ear 29 to which is pivotally pinned at 30 the upper bifurcated end of the nozzle elevator rod 31. The lower portion of this rod is bent forwardly and ends in a ring 32 which embraces the nozzle 8 and is anchored thereto by set screws 33, at a spaced distance from the lower end of the sleeve 6, so as to permit 70 a certain vertical reciprocation of the nozzle 8 within the sleeve 6. Thus it will be noted that as the handle 18 is depressed, the nozzle 8 will be raised into the sleeve 6; also that the nozzle may be at the same time partially rotated by merely swinging the handle 18 from side to side.

Interiorly, the circular wall of the housing 1 is slightly flared outwardly from bottom to top, as shown at 34, and a complementarily 80 tapered annular valve sleeve 35 is seated within the housing and adapted to rotate snugly against the said circular face of the housing and over the ports 2 and 3. This valve sleeve is formed with hot and cold 85 water ports 36 and 37 adjacently positioned within a half circumference of the sleeve 35, and the sleeve is also formed with two diametrically opposite guide bosses 38, elongated vertically partially across the inner 90 face of the sleeve 35. The lower edge of the valve sleeve 35 falls slightly short of contacting with the bottom of the housing 1 as shown at 39, whereby the wear upon the meeting surfaces is compensated for by the 95 gradual descent of the tapered sleeve. A coil spring 40 serves to press the sleeve 35 steadily downward to its seat, the said spring being pressed between the cover 9 and the annular shoulder 41 formed around the upper margin 100

of the sleeve 35. A double valve assembly is mounted centrally within the housing 1, consisting of a primary tubular valve 42 slotted vertically through its upper portion as shown at 43 to accommodate the flow of water and having a lower beveled annular lip 44 to coact with the seat 7. The upper inset portion 45 of the valve 42 extends into the cage 11 as shown. A coil spring 46, 10 rounding the upper inset portion 45 of the valve 42 and braced between the cover 9 and the annular shoulder 47 of the valve, serves to press the valve to its seat.

The valve 42 is formed with the inner, annular, beveled secondary valve seat 48 at the base of the upper tubular portion 45, and a smaller, cylindrical, secondary valve 49 having a beveled bottom 50 for coacting with the seat 48, is reciprocatingly mounted with- 20 in the upper tubular inset portion 45 of the valve 42. A coil spring 51, braced between the cage 11 and the bottom of the valve 49, serves to press the latter to its seat.

The annular shoulder 47 of the primary valve 42 is recessed at diametrically opposite points as shown at 52 for slidably engaging the bosses 38 of the sleeve 35. Thus the valve 42 may be raised without raising the sleeve 35, but the rotation of the valve 42 serves to 30 rotate the sleeve 35 also through the engagement of the bosses 38 with the recesses 52. Water ports 53 are formed through the primary valve 42 to permit the free flow of water. The upper and inner end of the nozzle 8 is cut away at each side so as to leave oppositely disposed fingers 54, the extremities of which are connected by a bridge piece 55 having an upwardly extending lug 56. The fingers 54 slidably engage grooves 57 formed vertically in the inner peripheral wall of the lip 44 of the valve 42, and the arrangement and adjustment is such that upon the upward movement of the nozzle 8 within the sleeve 6, the lug 56 will impinge 40 upon the bottom 50 of the secondary valve 49 and so raise that valve slightly before the bridge 55 strikes the annular base 58 of the primary valve 42 and so raises that valve also. The purpose of this arrangement is, since 50 the water pressure upon the upper surfaces of the valves 42 and 49 may be considerable and hard to overcome by downward pressure upon the handle 18, to first partially relieve this pressure by the elevation first of the 55 secondary valve 49 and then the primary valve 42.

In use and operation, the handle 18 may be readily swung horizontally to rotate the sleeve 35 to properly position the ports 36 and 37 for the delivery of hot, cold or warm water, after which by depressing the handle 18, the valves 42 and 49 are opened for the flow of water as above stated. By then press- 65 ing the latch 22 inwardly so that the nose 21

thereof engages the notch 20 of the ear 16, the handle may be locked in its depressed position for the continuous flow of water until the handle is released.

While I have herein described a certain specific manner and method of constructing and assembling the elements of my invention, it is understood that I may vary from the same in minor details, not departing from the spirit of my invention, so as best to construct a practical device for the purpose intended, as defined in the appended claims.

I claim:

1. In a device of the kind described, a housing, a sleeve mounted through the bottom of the housing, a nozzle rotatably and slidably mounted through the sleeve, and means supported from the top of the housing and extended exteriorly thereof to the lower side thereof and there connected with the said nozzle for simultaneously rotating and reciprocating the nozzle within the sleeve.

2. In a device of the kind described, a cylindrical housing having its inner peripheral wall flared from end to end and having spaced water ports formed through said wall, a complementarily tapered valve sleeve rotatably seated within the housing over said ports, the said sleeve having water ports 90 adapted to cooperate with the ports of the housing for the delivery of water, and means for rotating the said sleeve, said means being supported upon the housing and extended exteriorly thereof and connecting with the said sleeve through an opposite portion of the housing.

3. In a device of the kind described, a cylindrical housing having its inner peripheral wall flared from end to end, and having spaced water ports formed through said wall, a complementarily tapered valve sleeve rotatably seated within the housing over the said ports, the said sleeve having water ports adapted to cooperate with the ports of the housing for the delivery of water, a nozzle rotatably and slidably mounted through an end of the housing, a valve assembly upon the upper inner end of the nozzle, rotatable therewith and adapted to be opened upon the inward movement of the said nozzle, and a connection between the valve assembly and the said valve sleeve for rotating the sleeve with the nozzle and valve assembly.

4. In a device of the kind described, a cylindrical housing having its inner peripheral wall flared from end to end and having spaced water ports formed through said wall, a complementarily tapered valve sleeve rotatably seated within the housing over the 125 said ports, the said sleeve having water ports adapted to cooperate with the ports of the housing, a nozzle rotatably and slidably mounted through the narrowed end of the housing, the inner end of the nozzle having 130

oppositely positioned fingers extended parallel with the axis of the nozzle, a bridge piece connecting the extremities of the fingers, a lug extended from the bridge piece, a primary valve within the housing opposite the inner end of the nozzle, the same being formed to slidably engage the said fingers of the nozzle end, being adapted to be opened by the inward movement of the nozzle and having a 10 sliding connection with the said valve sleeve transversely of the periphery of the sleeve, and a secondary valve seated upon the primary valve and adapted to be opened by the said lug of the bridge piece at the end of the 15 nozzle in advance of the opening of the primary valve.

5. In a device of the kind described, a cylindrical housing having its inner peripheral wall flared from end to end and having 20 spaced water ports formed through said wall, a complimentarily tapered valve sleeve rotatably seated within the housing over the said ports, the said sleeve having water ports adapted to cooperate with the ports of the 25 housing, a nozzle rotatably and slidably mounted through the narrowed end of the housing, the inner end of the nozzle having oppositely positioned fingers extended parallel with the axis of the nozzle, a bridge piece 30 connecting the extremities of the fingers, a lug extended from the bridge piece, a primary valve within the housing opposite the inner end of the nozzle, the same being formed to slidably engage the said fingers 35 of the nozzle end, being adapted to be opened by the inward movement of the nozzle and having a sliding connection with the said valve sleeve transversely of the periphery of the sleeve, a secondary valve seated upon 40 the primary valve and adapted to be opened by the said lug of the bridge piece at the end of the nozzle in advance of the opening of the primary valve, a handle mounted upon the housing and adapted for swinging movement in perpendicular planes, and a connection 45 between the handle and the protruding end of the said nozzle for moving the latter with the former.

6. A combination water faucet, comprising 50 a suitable casing with openings for the entrance of hot and cold water and for a depending nozzle, a nozzle slidably mounted in the nozzle opening of the casing, a primary valve having a reduced central aperture 55 seated over the upper end of the said nozzle and adapted to be raised by the upward movement of the nozzle, a secondary valve mounted upon the primary valve, a lug extended from the upper end of the nozzle and adapted 60 to raise the secondary valve in advance of the primary valve, means for raising the said nozzle, and means for controlling the flow of water into the casing through the said water openings.

65 7. A combination water faucet, comprising

a suitable casing, a cap rotatively mounted upon the casing, a handle pivoted upon the cap for vertical movement, a handle bar extended from the handle below the said casing a nozzle slidably journaled through the 70 lower side of the casing and supported upon the lower end of the said handle bar, two interdepending valves mounted within the casing arranged to be raised one in advance of the other by the upward movement of the said 75 nozzle, and means for admitting hot or cold water in varying proportions into the said casing.

In testimony whereof I affix my signature.
